CASE FOR BATTERY POWERED ORTHOPEDIC
SURGICAL DRILL

Meyer Fishbein, 12020 Saltair Place,
Los Angeles, Calif. 90049

Filed Sept. 7, 1971, Ser. No. 178,544

Term of patent 14 years

Int. Cl. D24—02

U.S. Cl. D83—12

FIG. 1 is a perspective view of a case for a battery powered orthopedic surgical drill showing my new design;

FIG. 2 is a side elevational view thereof;

FIG. 3 is a front elevational view thereof;

FIG. 4 is a bottom plan view thereof; and

FIG. 5 is a top plan view thereof.

I claim:

The ornamental design for a case for battery powered orthopedic surgical drill, substantially as shown and described.
